Ann T. C. Greenhalge's Ornamental Design for a Canopy, Stone.

Patented April 18, 1874.

Fig. 3

Des. 639

William J. Coggeshall, of Fall River, Mass.
Letters Patent No. 639 - Dated April 18th, 1854.

The schedule referred to in these Letters Patent, and making part of the same -

To all persons to whom these presents shall come:

Be it known that I, William J. Coggeshall, of Fall River, in the County of Bristol, and State of Massachusetts, have invented a new and ornamental design for a cooking stove, and I do hereby declare that the same is fully represented in the accompanying drawings, of which -

Figure 1 is a perspective view of a stove constructed according to the said design.

Figure 2 is a vertical section of the largest side door, and the side plate, with its base, moulding, and cornice.

Figure 3 is a horizontal section of the front plate and the front doors over the hearth, such section being taken midway through both the said doors.

The ornamental character of each foot E, is exhibited in front and end view by the perspective representations of them seen in Figure 1. The base A, is ornamented at top and bottom with chain work a, b, in relief, similar chain work being applied to the frieze directly under the cornice G. It is also extended around the panels of the several doors in the middle of each of which there is a rosette or ornamental flower formed as seen in the drawings. That on the door is surrounded by radial leaves or rays. The design is completed by the ornaments of the corners or junctions of the side and end plates, the hearth plate (C) and the top plate (B) being essentially like those in other stoves.

What I claim is the ornamental design for the side and end plates, the feet and the doors, as represented in the drawings.

In testimony whereof, I have hereunto set my signature
this twenty fifth day of March, A. D., 1854.
